UNITED STATES PATENT OFFICE.

HENRY O. POHRT, OF FLINT, MICHIGAN, ASSIGNOR TO A C SPARK PLUG COMPANY, OF FLINT, MICHIGAN, A COMPANY OF MICHIGAN.

COATING MACHINE.

Application filed January 16, 1926. Serial No 81,688.

An efficient means for coating such disks as figure wheels of odometers is the purpose of the coating machine constituting the subject matter of this invention. While designed and used for the specific purpose stated, the use for other purposes will be suggested to those having analogous problems to solve, and it is not intended to limit the scope of the invention to any single application.

One of the principal objects of the invention is to provide an apparatus in which a spindle for carrying a plurality of odometer registering wheels is rotated and simultaneously a pressure gun for delivering coating material is moved in a direction to deliver the coating material to the series of wheels. Another object is to provide a manual control for such an apparatus whereby upon a single operation the valve of the spraying gun is opened to eject the coating material, and the carriage having the spraying gun is moved in a direction to coat the several figure wheels.

Other objects will be obvious upon the reading of the detailed description which follows.

In the drawing accompanying the specification, Figure 1 is a side elevation of the apparatus. Figure 2 is a plan view. Figure 3 is an end view. Figures 4 and 5 are two sectional views each on the line 4-4 Figure 1, showing parts of the apparatus in two different positions. Figure 6 is a longitudinal section of a detail.

Referring now to the drawings illustrative of a single embodiment of the invention, numeral 1 shows a base or platform upon which the apparatus may be mounted. Upon this base is mounted an inclined plane 2. The inclined plane has at its lower end feet 3 and fastening means 4 by which the feet 3 are secured to the base 1. At the upper end of the inclined platform are legs 5 from which project feet 6 through which fastening means 7 pass to secure the feet 6 to the base 1. Extending lengthwise through the plane are two ways 8, one of these extending along one side of the inclined plane and the other extending lengthwise of the plane midway between the sides. These ways form guiding means for a travelling carriage 9. This travelling carriage is provided with clamping members 10 which surround the base 11 of a spray-

ing gun. The clamping members hold this base 11 in position by means of screw bolts 12 and wing nuts 13. The spray gun 14 is mounted upon the base by means of a stem 15. From the rear of the gun extends a connection 16 for a supply of coating material of any desired kind. Air under pressure is admitted through tube 17 and conduit 18. Suitable means in the form of an air valve is provided for admitting the compressed air into the gun. As this air valve is no part of the invention it need not be more particularly referred to. Extending lengthwise of the inclined plane, midway between the ways and parallel with and slightly beneath the plane is a screw rod 19. The screw rod 19 is journalled in the block 20 at one end and in the base of the inclined plane at the other end. At its lower end is mounted a pulley 21 by means of which the screw may be rotated. Depending from the carriage and extending through a slot 22 in the inclined plane, is a pivoted link member 23. This link member is formed as a half nut to engage the screw for the purpose of moving the carriage and the gun along the inclined plane. Simultaneous operation of the valve and the movement of the carriage along the plane is obtained by the use of a lever 24. This lever is connected to the half nut 23 and is also connected by a link 25 with a bell crank lever 26, the latter being operatively connected to the valve of the spray gun. It will be understood particularly by reference to Figures 4 and 5 that when the lever 24 is depressed from position shown in Figure 4 to that shown by Figure 5, the half nut engaging the screw and the valve is opened. In this latter position of the parts the carriage of the gun moves down the inclined plane and the paint or coating material is delivered by the gun.

At the other side of the inclined plane near the base is mounted a bifurcated bracket 27. The bifurcations 28 furnish bearings for a tubular rotating shaft 29. This tubular shaft has an enlargement 30 which limits its movement in one direction in the bearings 28. Adjacent the other bearing 28 is secured a pulley 31. The tubular opening in shaft 29 is enlarged at the lower end as shown at 32. Into the threaded end of this opening 32 is fastened a nut 33. Slidably in the tubular passage of shaft 29 is push rod 34. Push rod 34 has a knob 35

at its outer end serving as a handle and near its other end is an enlargement 36 positioned to move within the enlarged opening 32, the movement of push rod 34 being limited by engagement of part 36 with the nut 33 at one end and by engagement with the end of the enlarged opening 32 at its other end. Into the upper end of the tubular opening of shaft 29 may be inserted a spindle carrying a plurality of figure wheels 37 to be coated. Owing to the angular position of the spindle the figure wheels may be slipped on to the spindle and will remain in position under the influence of gravity, it being unnecessary to provide any means to hold the wheels in their assembled position. From an examination of Figure 6, to be seen when the push rod 34 is at its outermost position, the spindle carrying the figure wheels may be inserted in the tubular opening in the shaft 29. When it is desired to remove the figure wheels 37 with the spindle from shaft 29 the rod 34 may be pushed inwardly and the spindle carrying the wheels 37 will be forced out from the opening into the shaft.

The pulleys 21 on the screw shaft and 31 on the tubular shaft are arranged to be simultaneously driven by a belt 38 engaging these pulleys and also engaging a pulley 39 on the counter shaft 40. This counter shaft may be driven directly by a motor or driven indirectly from any source of power.

The operation of the machine will be readily understood from the foregoing description without any extended explanation. A convenient number of odometer figure wheels or other articles to be coated are placed upon a spindle which latter is then

inserted in the appropriate end of the tubular shaft. Preparatory to setting the mechanism into operation, the carriage is moved to the upper end of the inclined plane. The counter shaft carrying the driving pulley is now set into operation, causing the rotation of the screw rod and of the spindle carrying the figure wheels to be coated. The operator then depresses the lever whereupon the half nut engages the driven screw and the valve is opened to air pressure. The carriage then moves down the inclined plane and the rotating wheels will be coated with the material from the gun.

I claim:

1. An apparatus for coating rotating articles including a moving carriage carrying the spraying gun, the gun having valve operating means, mechanical means for moving the carriage, and manually operating means for simultaneously applying the mechanical means and moving the valve operating means.

2. In a coating apparatus, an inclined plane, a rotating spindle carrying shaft parallel with said plane, a spray gun carriage movable along the plane in a direction parallel to said shaft, a rotating screw rod parallel to the plane and beneath the carriage, pulleys on the shaft and screw rod, a belt simultaneously driving both pulleys, the spray gun having a valve control, means to simultaneously open the valve control and to apply the rotation of the screw rod to the movement of the carriage.

In testimony whereof I affix my signature.

HENRY O. POHRT.
